UNITED STATES PATENT OFFICE.

AXEL H. STAF, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A SPOON OR SIMILAR ARTICLE.

Application filed February 25, 1922. Serial No. 901. Term of patent 14 years.

To all whom it may concern:

Be it known that I, AXEL H. STAF, a citizen of the United States of America, residing at Providence, in the county of Providence and State of Rhode Island, have invented a new, original, and ornamental Design for a Spoon or Similar Article, of which the following is a specification, reference being had to the accompanying drawing, forming a part thereof.

Figure 1 shows a perspective of the front of the design.

Figure 2 a side view.

Figure 3 a vertical section.

Figure 4 a rear view of the handle.

Figure 5 a section along the line 5—5 of Figure 1.

Figure 6 a section along the line 6—6 of Figure 1.

Figure 7 shows an enlarged view of the upper part of the handle.

I claim:—

A spoon or similar article embellished with the surface ornamentation as shown.

AXEL H. STAF.
